UNITED STATES PATENT OFFICE.

WILLIAM H. PHILLIPS, OF CHICAGO, ILLINOIS, ASSIGNOR TO HENRY PRATT COMPANY, OF CHICAGO, ILLINOIS, A CORPORATION OF ILLINOIS.

AUTOMATIC COAL-SPOUT-SWINGING DEVICE.

Application filed December 12, 1924. Serial No. 755,466.

My invention relates broadly to furnaces and more particularly to an automatic coal spout swinging mechanism.

An object of my invention is to provide 5 a mechanism of this type which may be employed to reciprocate a coal spout commonly used for feeding coal to a hopper of an automatic stoker.

A further object of my invention is to 10 employ a continuously traveling chain adapted to be clutched by the coal spout, the reciprocating motion of the coal spout by the chain being accomplished by the provision of improved means detachably 15 secured to the spout and functioning automatically to clutch the upper and lower runs of the chain when reaching the end of the travel each way.

A further object of my invention is to 20 provide a construction, which is simple, inexpensive and reliable in operation, and which may be employed to readily swing the spout to and fro across the front of the furnace by gripping preferably a chain 25 which is of the continuously traveling type.

An important feature of my invention resides in the particular construction used. A sprocket is employed as part of the clutching mechanism and associated with the 30 sprocket is a pair of pins of novel design alternately interlocking with the sprocket so as to restrain its rotation until tripped, and thereafter to allow the sprocket to advance and change its engagement with the 35 chain. This arrangement affords means for effecting an adjustment of the travel of the spout, and furthermore furnishes a simple and inexpensive motion reversing mechanism for the swinging coal spout. By 40 properly adjusting the tripping means, the travel of the clutching mechanism may be predetermined, irrespective of the length of the continuously traveling chain. On the other hand, any number of clutching mechanisms may be operated from a single drive. 45

I consider it an important object of this invention that the parts of the clutching mechanism, including the continuously 50 driven chain and the drive therefor, may be arranged as a unitary assembly within a single casing. Standardization is thereby possible and I am able to furnish the mechanism as a unit capable of attachment at the front of furnaces of many types and 55 sizes.

At times it is highly desirable to feed the coal manually to the fire, when the fire is to be kept low, while, on the other hand, coal of desirable quality from a certain overhead bunker may be wanted through a certain spout. To meet these requirements, it is preferable to arrange the swinging spout detachable from the clutching mechanism, and to this end, I have novelly designed the 60 mechanism to be quickly releasable from the 65 spout without altering the construction or operation thereof.

These and other objects will appear from the following detailed description of a preferred embodiment of my invention when 70 read in connection with the accompanying drawings, which form a part hereof.

In the drawings:

Figure 1 is a side elevational view of a furnace having an automatic stoker and a 75 swinging coal spout and illustrating the manner of adapting my invention thereto.

Fig. 2 is a front elevational view of a reciprocating mechanism embodying my invention and illustrating it as a unitary 80 assembly which may be attached across the front of a furnace.

Fig. 3 is a rear view of this mechanism.

Fig. 4 is a detailed sectional view of the left hand end of the mechanism as shown 85 in Fig. 2, with a cover plate removed to illustrate the drive thereof.

Fig. 5 is a detail view taken at the rear of the same end, illustrating the releasing means employed to change the engagement 90 of the clutching mechanism with the upper and lower runs of a continuously driven chain.

Fig. 6 is an enlarged sectional view, taken on line 6-6 of Fig. 2;

Fig. 7 is an enlarged front view of the clutching mechanism, with a cover plate removed, however, to illustrate the manner in which the sprocket engages the chain; and

Figure 8 illustrates the spout in section 100 but shows the manner in which the clutching mechanism loosely embraces the same in detachable relation.

I preferably embody my invention in a mechanism capable of attachment as a unit 105 at the front of a furnace A and provide a drive extending at one end of the mechanism for engaging a drive operating the automatic stoker B. An advantage is obtained by this arrangement, in that, I am 110

able to standardize the mechanism and adapt it to practically any make of stoker or furnace having a swinging spout for feeding fuel thereto. Moreover, when the mechanism is designed in the form of a unit, the arrangement more readily permits the mechanism to be disconnected from the spout in order to operate the latter manually when so desired.

10 An elongated or rectangular casing 2 of channel formation, as illustrated in Fig. 1 is provided with a trackway 3 in its rear wall 4. The edges of the channel casing are turned inwardly toward each other to form 15 the upper and lower flanges 5. This casing may be attached at the front of furnace A in any suitable manner, say by the bars 6 shown in Fig. 1.

A clutching mechanism, in the form of a 20 reciprocating shuttle, is provided for movement within casing 2, the upper and lower flanges 5 serving slightly to overlap and retain the mechanism within the casing.

At the ends of casing 2, sprockets 7 and 25 8 are suitably mounted for rotation. An endless chain 10 may be entrained over these sprockets and may be driven through the sprocket 7 which is provided with a drive connecting with the drive of stoker B.

30 This drive comprises a gear 11 on a shaft 12 carrying sprocket 7, and a similar gear 13 on a shaft 14 which extends through a cover plate 15 and has a sprocket 16 at its outer end. A chain 17 is adapted to be entrained over sprocket 16 and mesh with a gear 18 comprising part of the drive of stoker B. Adjustable take-up means may be provided for keeping the chain taut by mounting the end sprocket 8 on a shaft extending in a block 20 at the rear of casing 2. Block 20 is adjustable in track-way 3 by means of a screw 21 extending through plate 22. Nuts 23 may be threaded either way on the screw 21 to vary the position 45 of the block 20 and consequently the sprocket 8 carried thereby.

The clutching mechanism comprises a housing 25 having the vertical side lugs 26, in which rollers 27 may be mounted for 50 movement along the track-way 3. A sprocket 28 is rotatably mounted within this housing 25 by means of a bolt 29. This bolt is provided with a threaded portion entering the housing 25 and has a collar 30 55 about its cylindrical portion, on which the sprocket 28 rotates. The bolt 29 also serves to secure a cover plate 31 to the front of the housing 25, this cover plate being provided with outwardly extending lugs 32 for 60 receiving a spout engaging yoke member 33. I preferably secure yoke 33 to cover plate 31 by means of pins 34, which may at any time be removed to release this yoke 33.

At the rear of housing 25, a bar 38 may 65 be secured. Internally threaded transverse

bosses 39 are formed integrally and have their apertures adapted alternately to register with a series of openings 40 in sprocket 28. This sprocket may be reinforced at both sides by disks 41 also having openings 70 cooperating with the openings 40 and comprising in fact a continuation thereof.

Sprocket 28 may have teeth 45 spaced a predetermined distance apart, which are preferably arranged in pairs equal to the 75 number of openings 40 in the sprocket. As will be noted in Fig. 7, the teeth 45 at the top of sprocket 28 are meshing with the continuously driven chain 10. As I shall later explain, this sprocket may be released 80 from mesh with the upper run of chain 10 and may be allowed to advance clockwise slightly so that opening 40^a will register with the dotted circle 46. The advancing movement of the sprocket is accomplished by 85 means which I shall later describe, and which may be employed for temporarily holding the sprocket locked against rotation during the time the clutching mechanism is moving from one end to the other of casing 90 21. This means serves to release the sprocket, and the chain 10 will rotate the latter slightly to bring this opening 40^a in register with the dotted circle 46, whereupon the sprocket is again locked against 95 rotation. The teeth designated 45^c will then be in mesh with the lower run of the chain 10 and the movement of the clutching mechanism will be reversed.

This means comprises a pair of pins 100 48 and 49, which have threaded shanks 50 and 51, respectively, one having a right handed thread, and the other having a left handed thread. The inner ends of the pins are reduced as indicated at 52 and are free 105 to move into the openings 40 in sprocket 28 when brought in register therewith. The pitch of the threads 50 and 51 is such that slight rotational movement of the pins 48 and 49 will move the latter a distance sufficient to engage or withdraw the portions 52 thereof from the openings 40, as the case may be. It will be noted in Fig. 7 these pins are arranged in a manner to allow but one to enter an opening 40 at any one time. 115 Consequently, if the pin 48 is engaging in one of the openings 40 to lock the sprocket 28 against rotation, the pin 49 is withdrawn.

Fingers 53 and 54 are secured to the ends 120 of the pins 48 and 49 respectively. A spring 55 interconnects these fingers at their lower ends. At the opposite ends of casing 21, I have so arranged a pair of brackets 56 that 125 tripping members 57 and 58 provided thereon are in the path of movement of the upper ends of fingers 53 and 54. These tripping members may take the form of rollers, if so desired. When the clutching mechanism is moved to the right as shown in Figs. 3 and 130

5, the roller 58 is adapted to engage the finger 53 and pivot it to a vertical position, as illustrated in Fig. 5. This causes the spring 55' to be placed under tension, thereby influencing the finger 54 to likewise move to its vertical position. This movement, however, is restrained until the sprocket 28 has rotated slightly so as to bring the opening 40^a into alignment with the dotted 10 circle 46, which in Fig. 7 represents the pin 49 in back of the sprocket. In other words, the sprocket is rotated so as to bring the opening 40^a in register with this pin 49. Being under spring tension, the pin 49 is now rotated to its vertical position, such 15 movement being sufficient for the threads 51 to carry the pin 49 inwardly a distance sufficient to lie in the opening 40^a. After the sprocket has rotated, the pin 48 is prevented 20 from again engaging in one of these openings 40 until a similar operation occurs at the other end of the casing 21, so as to withdraw the pin 49 and allow the sprocket 28 to again rotate or advance and permit 25 pin 48 to engage again.

Yoke 33 serves to engage a coal spout 55 having a flexible joint 56 at its upper end to permit the spout to swing to and fro across the front of the furnace A. Automatic stoker B is furnished with the usual coal hopper 57, into which the coal spout 55 feeds. It is common to extend a bar 58 across the front of the hopper 57 for guiding the coal spout 55, this spout being provided 30 with an anti-friction roller 59 which engages the bar 58. A handle 60 usually extends downwardly a distance to be accessible for manually reciprocating the spout 55. I find that it is preferable to arrange my improved spout swinging mechanism, so that it can be readily detached from the spout to allow manual operation by means of the handle 60. This is often desirable when there is a low fire and hand feeding is necessary, or, when access to the coal in the overhead bunker 61 is desirable, due to the quality of the coal and the desire to use it for a particular purpose. Yoke 33 is pivotally mounted on the pins 34 carried by the cover 35 31, and therefore, may be readily released from the spout by moving upwardly about these pins.

I shall now describe the operation of the device.

Assume that the clutching mechanism is approaching the left hand end of the casing as is illustrated in Fig. 2. Sprocket 28 will be in mesh with the upper run of chain 10 traveling in the direction of the arrow in this figure. It will be remembered, of course, that this sprocket is locked against rotation due to the pin 48 engaging in one of the openings 40. As soon as the finger 53, however, engages roller 58, as is illustrated in Fig. 5, pin 48 is withdrawn.

Sprocket 28 will slip about its pivot until another opening 40 registers with the pin 49. Movement of the pin 48 out of interlocking engagement with the sprocket 28 causes the spring 55' to be placed under tension and thereby exert a force against the finger 54, which force will immediately revolve the pin 49 when one of the openings 40 registers with the pin. The teeth 51 are of considerable pitch and of a different hand than that of teeth 50 on pin 48. Consequently, the pin 49 will be brought into engagement with the registering opening 40 and the sprocket 28 held against further slipping about its pivot. Such slipping of the sprocket 28 is for the purpose of bringing the teeth 45^c in mesh with the lower run of chain 10. The clutching mechanism is now locked to the lower run of the chain and caused to travel to the right. The same tripping action and releasing of the sprocket 28 so as to change its mesh from the lower to the upper run occurs when the finger 54 strikes against the roller 57. Hence, it will be noted that the clutching mechanism is permitted to move to and fro within the casing 21, its reversing movement occurring as soon as it reaches the ends of the casing 21.

As before pointed out, I novelly arrange the various parts of the mechanism within the casing 24 so as to provide a unitary assembly. This assembly is capable of attachment to many types of furnaces, thereby permitting standardization of the parts. I have found, as a general rule, that the casing may fit across the front of furnaces of different sizes. The travel of the clutching mechanism may be predetermined by providing the plates 56 of the tripping means adjustable. These plates are provided with bolts 60' which extend through the opening 3 in casing 21 and hold clamping plates 61 in position against the side of the casing opposite to the plates 56 in order to clamp the latter in position. Should the width of the furnace require a shorter travel of the clutching mechanism than that shown in the drawings, both plates 56 may be moved toward the center. On the other hand, should the travel of the clutching mechanism be restricted at one end only, the adjacent plate 56 may be moved toward the center. In other words the arrangement is such that the travel may be quickly changed without requiring any change to be made in the casing, chain 10 or the position of its end sprockets 7 and 8, or in the drive thereof, whether this drive is taken from the stoker drive or from a motor employed especially therefor.

Various modifications and other embodiments of my invention are possible, and consequently, I do not intend to be limited to the exact disclosure shown herein.

I claim:

1. In a mechanism for use with an automatic stoker provided with a swinging spout for feeding fuel evenly from end to end to a hopper of a furnace comprising an assembly, which in its entirety is fastened as a unit to the front of said furnace, and means mounted to readily swing into engagement with said spout for reciprocating said spout. 65
2. In a mechanism for use with an automatic stoker provided with a swinging spout for feeding fuel evenly from end to end to a hopper of a furnace comprising an assembly embodying a continuously driven chain, a spout embracing means alternately engaging the upper and lower runs of said chain, and a casing for housing said parts. 70
3. In a mechanism for use with an automatic stoker for feeding fuel evenly from end to end to a hopper comprising a casing 20 for fitting across the front of the furnace, and a clutching mechanism arranged to travel to and fro within said casing and to detachably connect to a coal swinging spout, said casing and said clutching mechanism 25 being secured as a unit to the front of said furnace. 75
4. In a mechanism for use with an automatic stoker for feeding fuel evenly from end to end to a hopper comprising a casing 30 for fitting across the front of the furnace, a clutching mechanism arranged to travel to and fro within said casing and operably to connect to a coal swinging spout, and means operably connected to the drive of said 35 stoker for driving said clutching mechanism in timed relation to the operation of said stoker, said casing embodying said clutching mechanism and said driving means as a unitary assembly for mounting at the front of 40 the furnace. 80
5. In a mechanism for use with an automatic stoker for feeding fuel evenly from end to end to a hopper comprising a swinging spout, means for feeding fuel to said spout, clutching means at the lower end of the spout adjacent to said hopper, and a continuously rotating member connected to and operated by the drive of said automatic stoker having its upper and lower runs alternately engaged by said clutching means for reciprocating said spout according to the rate of speed at which said stoker is driven. 85
6. In a mechanism for use with an automatic stoker for feeding fuel evenly from end to end to a hopper comprising a swinging spout, means for feeding fuel to said spout, clutching means at the lower end of said spout adjacent to said hopper including a sprocket, and a continuously rotating chain having its upper and lower runs alternately engaged by said sprocket for reciprocating said spout. 90
7. In a mechanism for use with an automatic stoker for feeding fuel evenly from end to end to a hopper comprising a swinging spout, means for feeding fuel to said spout, clutching means at the lower end of said spout including a sprocket and a pair of pins associated therewith for alternately engaging openings in the sprocket, and a continuously rotating member having its upper and lower runs alternately engaged by said sprocket for reciprocating said spout, the alternating engagement of said pins with said sprocket reversing the movement of said spout. 95
8. In a mechanism for use with an automatic stoker for feeding fuel evenly from end to end to a hopper comprising a swinging spout, means for feeding fuel to said spout, clutching means operably connected to said spout including a sprocket, a pair of pins alternately engaging in openings in said sprocket and means for interconnecting said pins whereby withdrawal of one pin tends to engage the other pin in said sprocket, and a continuously rotating member having its upper and lower runs alternately engaged by said sprocket for reciprocating said spout, the alternating engagement of said pins with said sprocket reversing the movement of said spout. 100
9. In a mechanism for feeding fuel to a furnace comprising a swinging spout, means for feeding fuel to said spout, clutching means including a sprocket having teeth spaced a predetermined distance apart, said clutching means being operably connected to said spout, and a continuously rotating member having its upper and lower runs alternately engaged by the spaced teeth of said sprocket for reciprocating said spout. 105
10. In a mechanism for use with an automatic stoker provided with a swinging spout for feeding fuel evenly from end to end to a hopper of a furnace comprising clutching means for reciprocating said spout, a casing for housing said clutching means, gears at the ends of said casing, and a continuously driven member running over said gears and having its upper and lower runs adapted for alternate engagement with said clutching means. 110
11. In a mechanism for use with an automatic stoker provided with a swinging spout for feeding fuel evenly from end to end to a hopper of a furnace comprising clutching means for reciprocating said spout, a casing for housing said clutching means provided with an opening therein serving as a track for said clutching means, a continuously driven member having its upper and lower runs adapted for alternate engagement with said clutching means, and means on the rear of said casing adjacent the ends of said track opening adapted to engage a projecting portion of the clutching means for releasing the same from one of the runs of said con- 115 120 125

tinuously driven member and simultaneously engaging it with the other run.

12. In a mechanism for use with an automatic stoker provided with a swinging spout for feeding fuel evenly from end to end to a hopper of a furnace comprising a clutching mechanism detachably secured to said spout for reciprocating the same, a casing for housing said clutching mechanism where-
5 by the same may be mounted at the front of said furnace in the form of a unit, and a drive extending at one end of said casing for connecting with the drive of said stoker whereby the fuel feeding through said spout
10 may be supplied to said hopper in proportion to the operation of said stoker.

13. In a mechanism for use with an automatic stoker provided with a swinging spout for feeding fuel evenly from end to end to a hopper of a furnace comprising a casing having a trackway therein, rollers adapted to be guided in said trackway, a housing, a sprocket rotatably mounted on said housing, a continuously driven chain having its upper and lower runs alternately meshing with said sprocket, and means adapted to advance said sprocket when reaching the end of said trackway so as to change the engagement of said sprocket with the upper and lower runs of said chain.
20

14. In an automatic reciprocating mechanism for use with a spout for feeding fuel to a furnace, a continuously driven chain, a sprocket adapted alternately to engage the upper and lower runs of said chain, means for detachably securing said spout to said mechanism, and means for permitting said sprocket to advance when reaching the ends of its travel for changing the engagement thereof with the upper and lower runs of said chain.
30

15. In an automatic reciprocating mechanism for use with a spout for feeding fuel to a furnace, a continuously driven chain, a sprocket adapted alternately to engage the upper and lower runs of said chain, means for detachably securing said spout to said mechanism, and means comprising pin members adapted alternately to interlock with said sprocket and to permit said sprocket to thereby change its engagement with the upper and lower runs of said chain.
40

16. In an automatic reciprocating mechanism for use with a spout for feeding fuel to a furnace, a continuously driven chain, a sprocket provided with a plurality of openings adapted alternately to engage the upper and lower runs of said chain, means for detachably securing said spout to said mechanism, and means comprising pin members for alternately engaging in said openings so as to change the engagement of said sprocket with the upper and lower run of said chain and reverse the movement of said spout.
50

17. In an automatic reciprocating mechanism for use with a spout for feeding fuel to a furnace, a continuously rotating chain, a sprocket for alternately engaging the upper and lower runs of said chain, means for detachably securing said spout to said mechanism, means comprising pin members for changing the engagement of said sprocket with the upper and lower runs of said chain, and means for tripping said pin members to secure alternate engagement thereof with said sprocket so as to permit a predetermined advance of said sprocket and a consequent change in mesh with said chain.
60

18. In an automatic reciprocating mechanism for use with a spout for feeding fuel to a furnace, a continuously driven chain and end rollers therefor, a casing supporting said rollers and a trackway provided in said casing, a housing having a sprocket rotatably mounted thereon and movable along said trackway, tripping elements at the ends of said trackway, and means cooperating with said tripping elements for alternating the engagement of said sprocket with the upper and lower runs of said chain.
70

19. In an automatic reciprocating mechanism for use with a spout for feeding fuel to a furnace, a continuously driven chain and end rollers therefor, a casing supporting said rollers and a trackway provided in said casing, a housing having a sprocket rotatably mounted thereon and movable along said trackway, tripping elements at the ends of said trackway, and means cooperating with said tripping elements for alternating the engagement of said sprocket with the upper and lower runs of said chain, said means comprising a pair of pins engaging said sprocket one at a time.
80

20. In an automatic reciprocating mechanism for use with a spout for feeding fuel to a furnace, a continuously driven chain and end rollers therefor, a casing supporting said rollers and a trackway provided in said casing, a housing having a sprocket rotatably mounted thereon and movable along said trackway, tripping elements at the ends of said trackway, and means comprising a pair of pins for alternately engaging said sprocket and having right and left handed threaded shanks, said shanks threading into said housing, the threads of each being of a pitch permitting axial movement of the pins sufficient to engage or withdraw the same by a slight rotation thereof.
90

21. In a mechanism for use with an automatic stoker provided with a swinging spout for feeding fuel evenly from end to end to a hopper of a furnace comprising a clutching mechanism arranged to travel to and fro across the front of the furnace in engagement with said spout, a trackway for said clutching mechanism, and means for
100
110
115
120
125

- reversing the movement of said clutching mechanism between predetermined points along said trackway.
22. In a mechanism for use with an automatic stoker for feeding fuel evenly from end to end to a hopper of a furnace comprising a clutching mechanism arranged to travel to and fro across the front of the furnace and to detachably connect to a coal 10 swinging spout, and means for mounting said clutching mechanism between said furnace and said spout.
23. A spout swinging device comprising a shuttle, and a connection with said shuttle 15 including a pivotally mounted yoke-like member adapted to be pivotally lifted into and out of engagement with a spout.
24. In a mechanism for swinging a spout substantially from end to end of a hopper 20 including means for guiding said spout along said hopper, the combination with means arranged to travel to and fro across said hopper and having means provided thereon for loosely embracing said spout to provide a 25 detachable connection therewith.
25. In a mechanism for swinging a spout substantially from end to end of a hopper including means for sustaining the weight 30 of the spout during its movement along the hopper, the combination with means arranged to travel to and fro across the hopper and having provisions for loosely embracing 35 said spout.
26. In combination with an automatic 40 stoker, and a hopper therefor, a swinging chute arranged to move back and forth to distribute coal along said hopper, an endless belt extending parallel to the movement of said swinging chute, means for driving said 45 belt, a reciprocating device movable in a plane parallel to said belt and operably driven by said belt, and a yoke loosely embracing said swinging chute and pivotally connected to said reciprocating device.
27. In combination with an automatic 50 stoker and a hopper therefor, a swinging chute arranged to move back and forth to distribute coal along said hopper, an endless belt extending parallel to the swinging 55 of said swinging chute, a track, a shuttle provided with rollers for movement along said track, means for connecting said shuttle to said chute, and means connecting said shuttle to a point on said chain.
28. In combination with an automatic 60 stoker, and a hopper therefor, a swinging chute arranged to move back and forth to distribute coal along said hopper, a frame 65 provided with a trackway mounted adjacent to said hopper, a shuttle provided with means for guiding the shuttle along said trackway in a plane adjacent thereto, means for connecting said chute to said shuttle, and means for connecting said shuttle to a point on said chain.
29. In combination with an automatic 70 stoker, a hopper therefor, and a swinging chute arranged to move back and forth to distribute coal along said hopper, of a mechanically operated chute swinging device 75 comprising a member continuously moving through a predetermined path which lies substantially parallel to the swinging of said swinging chute, a connection between said member and said swinging chute, said connection including a shuttle-like member having pivotal means for connecting it to said chute and means for also connecting it to said continuously movable member.
30. In combination with an automatic 80 stoker, a hopper therefor and a swinging chute arranged to move back and forth to distribute coal along said hopper, of a mechanically operated chute swinging device 85 comprising an endless belt extending substantially parallel to the swinging of said swinging chute, a shuttle, a trackway for guiding said shuttle, a connection for attaching said swinging chute to one side of said shuttle, and a second connection for attaching said belt to the other side of said 90 shuttle.
31. In combination with an automatic 95 stoker, a hopper therefor and a swinging chute arranged to move back and forth to distribute coal along said hopper, of a mechanically operated chute swinging device 100 comprising a continuously driven chain, a frame for carrying said chain, a trackway on said frame, rollers for supporting in suspended relation at one side of said frame a shuttle which is adapted to be connected to said chute and to said chain.
32. In combination with an automatic 105 stoker, a hopper therefor and a swinging chute arranged to move back and forth to distribute coal along said hopper, of a mechanically operated chute swinging device 110 comprising an endless belt, means for driving said belt, a shuttle for connecting said swinging chute to a point on said belt, a trackway along which said shuttle moves, and roller members for supporting said shuttle on said trackway.

In witness whereof, I have hereunto subscribed my name.

WILLIAM H. PHILLIPS.
